UNITED STATES PATENT OFFICE.

WALTER I. LEATHERLAND, OF ALEXANDRIA, VIRGINIA, ASSIGNOR OF ONE-HALF TO
JAMES S. FRANCIS, OF RICHMOND, VIRGINIA.

RECORD-BOOK.

1,195,038.

Specification of Letters Patent. Patented Aug. 15, 1916.

Application filed June 2, 1914. Serial No. 842,505.

To all whom it may concern:

Be it known that I, WALTER I. LEATHERLAND, a citizen of the United States, residing at Alexandria, Alexandria county, and 5 State of Virginia, have invented and discovered certain new and useful Improvements in Record-Books, of which the following is a specification.

My invention consists in certain improvements in the arrangement of record books 10 designed especially for use in keeping a record of railway equipment in the yards of railway systems, it being designed especially to take care of such records for certain stipulated periods of time, as for example, 15 monthly, quarterly, or yearly records, the period depending upon the amount of business handled in the yard for which the record is designed, and limited to such periods as can be taken care of in a book of appropriate size for convenience in use and handling.

The improvements relate chiefly to a book 20 of the type employing what is known as the "third terminal system", and consists in making up the principal parts of such a book in sections for convenience, consisting of ten record sheets each, and following each of said sections with a sheet particularly designed for receiving overflow records from any of the ten preceding sheets, each sheet of each record section being arranged to take care of the terminals of ten successive numerals, and each of the overflow sheets being arranged to receive overflow memoranda 25 from any of the ten divisions of any of the ten preceding sheets. Such a record book is preferably composed of ten of such sections, thus providing in the entire book for 30 every numeral within the limit of six figures, which will take care of the number of any car known to be in service.

The invention further consists in supplementing the third terminal system for keeping track of the car movements with other columns and arrangements for recording memoranda relating to the cars which it is desired to preserve, whereby such memoranda may be quickly and conveniently located at any time, all of which results in a great saving of time and labor in the performance of the work, and also a great convenience in keeping the records in a most comprehensive and useful form, all as will

be hereinafter more fully described and 55 claimed.

Referring to the accompanying drawings which are made a part hereof and on which similar reference characters indicate corresponding parts, Figure 1 represents the first 60 sheet, being a double page, of the record book embodying my said invention, the three terminals indicated running from "000" to "900", Fig. 2 the first "overflow" sheet, or the overflow sheet belonging to the 65 first section of the book, being the eleventh sheet of the book, Fig. 3 is a figure similar to Fig. 1, except that it represents the first sheet, or double page, of the second section of the book and represents the last three 70 terminals from "010" to "910", Fig. 4 a view similar to Fig. 2, except that it represents the "overflow" sheet at the end of the second section of the book, Fig. 5 a double page of the record sheet for recording the movement of passenger equipment and Pullman equipment, respectively, Fig. 6 a page showing the record of the yard service for cars kept in the yard, Fig. 7 a view illustrating a page showing how the train records are 80 kept, Fig. 8 a detail view illustrating a portion of Fig. 1 at the top of the left-hand page, on a large scale, Fig. 9 a similar view as applied to Fig. 3, Fig. 10 a similar view as applied to Fig. 4, and Fig. 11 a detail 85 view showing a part of the matter illustrated at the top of Fig. 7 on an enlarged scale.

Referring now to Fig. 1, this figure illustrates the book as open at sheet 00, which 90 means the first sheet of the book, and further that the last two numerals of the car numbers recorded on these pages must end in "00", and the third terminal runs, respectively, from 0 to 9, each third terminal being given ten horizontal lines in two vertical divisions A. A. of each sheet, or double page, which is given four vertical divisions or spaces A. A. and B. B., relating to the car movements, as shown. Thus it will be 95 seen that on the page represented by Fig. 1, the spaces marked A. A. will take care of the car numbers ending in 00 and having the third terminal from 0 to 4, while the spaces marked B. B. will take care of numbers ending in 00 with the third terminal running from 5 to 9, and on the page represented by Fig. 3, the spaces A. A. will take

care of the numbers ending in 10 and having the third terminal from 0 to 4, while the spaces marked B. B. will take care of the numbers ending in 10 with the third terminal 5 to 9, as indicated. Subsequent pages will be correspondingly arranged in successive order. On this page the first column *a* will contain the numerals indicating the changes in the third terminals, of the horizontal divisions of the sheet. The next column *b* will contain the initial of the railway to which the car belongs. The next column *c* will contain the car number. The next column *d* will contain the initials indicating the railway from which the car was originally received by the yard and the date received, transferred from the previous periodical record. The next column *e* will indicate the class of the car, such as box, furniture, automobile, refrigerator, stock, coal, flat, ballast, coach, baggage, mail, express, Pullman, etc. The next space headed "Movements" is divided into a number of columns and each line into two divisions, an upper and a lower. The upper division is always used to indicate "received" information and the lower "forwarded" information. For example, the data inscribed on the top line in Figs. 3 and 9 would indicate that a Pennsylvania Railway car No. 131,010, was received on April 26th from the B. & O., forwarded to the Southern on April 27th, received from the Southern on May 2nd, forwarded to the B. & O. on May 3rd, received from the B. & O. on June 2nd, and forwarded to the Pennsylvania Railroad on June 2nd. In column *e* headed "Class" the information would be given that this was a box car. In the vertical space C are a number of columns, the first *f* for the initial of the car, column *g* for the car number, column *h* for the file number, and column *i* for special information. In this space it is intended to have recorded information relating to files containing information concerning claims and all correspondence or controversies over cars while in possession of the yard. In such cases each letter or other document relating to a specific car is given the number of the car and placed in a file which is numbered. By referring to the number of the car at any time the number of the file containing the record of the claim, or other correspondence, can be readily located and a great deal of time and labor ordinarily required in looking up such information is thus avoided. The second page of sheet 1 on Fig. 1 is a duplicate of the first, except that it takes care of third terminals from 5 to 9 instead of from 0 to 4. It will thus be noted that this sheet will take care of cars of any number, of six figures each, ending in 00 and with third terminals running from "0" to "9".

65 Referring now to Fig. 2, it will be noted

that this sheet is divided into ten vertical spaces and the 10 vertical columns headed "Car number" each contain 5 lines for each final terminal. Thus the first vertical space is divided into ten spaces of five lines each, the last terminal of which runs from 0 to 9 and the second and third terminals of which are 00. In the second column the second and third terminals are 10, the next column 20, the next 30 and so on across the page, which thus provides 100 spaces designed to take care of the overflow from each of the ten spaces of the ten preceding sheets in the book. One of these overflow sheets is inserted in the book after each successive section of ten sheets throughout the book. The main portion of the book thus contains 100 initial sheets and ten overflow sheets. By this means a yard record book is provided capable of receiving the record of all movements of cars from various roads, to and from the yard, of any number within the limits of six figures. It will also be noted that an overflow space is provided in the ten overflow sheets corresponding in terminal figures to each of the spaces provided for recording memoranda in the main records, which is a great advantage for the reason that it enables the main record sheets to be made somewhat smaller than would otherwise be necessary to take care of the same number of cars. In other words, the capacity of the book is materially increased without increasing its bulk or the number of pages in proportion. This is a great advantage for, as is well known, at certain periods an unusual or excessive amount of memoranda will be needed for certain cars or for the cars of certain roads, and even and uniform distribution of numbers is never the experience, which would make the ordinary provision, in equal divisions, for this memoranda inadequate. The excess, however, may be of a spasmodic character, both as to the particular cars or as to the particular road, and by means of the arrangement herein shown and described, the book is made of an "elastic" character, capable of ready and convenient use in taking care of this excess work and without unduly increasing the size of the book or its cost in manufacture.

In the drawings I have illustrated the first sheet and the overflow sheet of the first two sections of the book, and from this and the above description, the arrangement from the first one hundred and ten sheets, constituting the main body of the book, will be readily understood.

Following the main body of the book, consisting of 110 sheets, is a sheet (Fig. 5) especially designed to record the movement of passenger equipment, the left-hand page being designed for ordinary passenger cars and the right-hand page for Pullman cars.

In dividing the left-hand page, the movement space corresponds substantially to that of the freight car record shown on sheet 1 with a space for "remarks" following each movement line. The terminals printed on the page are only the final terminals, inasmuch as the numbers of passengers cars rarely exceed three figures. On the right-hand page is a record for Pullman cars, which are indicated by name and the names arranged in alphabetical order by having the spaces indicated by the different letters of the alphabet regularly spaced, as shown, with an "overflow" space in the last column, following "Z". Only two columns are indicated for movements because it is rarely that a Pullman car will need to have more than one or two movements recorded while under the jurisdiction of any one yard.

Referring to Fig. 6, here is shown one page of a yard service record sheet. It frequently happens that certain freight cars are retained in the yard for yard service, sometimes for a month, or maybe for several months. It is important that these cars also be kept located by a suitable record so that they may be found conveniently. On this sheet we have a column for the initials of the road owning the car, a column for the car number, a column for the class of service in which the car is used, a column for the kind of car, and 31 columns in which can be recorded the daily movements of the car, as from what part of the yard to what other part of the yard, from what track to what other track, or from what siding to what other siding, followed with a column for remarks in which any special information may be noted.

In Fig. 7 is illustrated a sheet intended for keeping a record of the trains received and forwarded daily. The first column indicates the date of the movement, the second column the class of train, the third column the number of the train, the next column the engine number, the next column the number of loaded cars, the next column the number of empty cars, the next column the total number of loaded cars, the next column the total number of empty cars, the next column the grand total of cars received during the day with an added space for remarks in which may be noted any special information thought advisable.

In Fig. 7 is indicated a one day movement, as on May 10th the first train noted was a local No. 61, engine No. 1412, containing twenty loaded and ten empty cars. The next train was perishable freight, train No. 73, engine No. 912, containing thirty loaded and ten empty cars. The next train was a "carded" or through freight, train No. 30, engine No. 312, containing ten loaded and ten empty cars. The next train was a slow freight, train No. 34, engine No. 916, con-

taining twenty loaded and ten empty cars. The total number of loaded cars received during the day were 80, the total number of empty cars 40, and the grand total 120 cars received. In the same manner on the opposite side would be noted the number of trains, kind of trains, and class of cars, and other information relating to trains forwarded from the yard.

Only a comparatively small number of sheets, indicated by Figs. 5, 6, and 7, will be required in a book. Following the first 110 sheets would be one or two sheets like Fig. 5, then one or two sheets like Fig. 6, except a double page, then one or two sheets like Fig. 7, except a double page. This would complete a record book ample to take care of the records of any yard for a month, and for many yards for a quarter, and for some yards for a much longer period of time.

By the arrangement of the columns showing the "home route", and the records of files containing records of claims and other controversies over cars (sheets 1 and 2), a great deal of time in searching records for this information is saved. By the arrangement of columns containing information relative to freight cars in the yard a great deal of time in searching for special cars belonging to certain companies is saved. By the record giving the information relative to the movement of cars within the yard, just the amount of service which each car is rendering, is easily determined and idle cars detected, thus often saving to the service cars that otherwise would be of no particular use for considerable periods of time.

The entire arrangement of the book is such that not only are the records of the equipment in the yard, and of the equipment received and forwarded, complete each day and in convenient form for use, but records are made of a nature that are the best and most advantageous for handling and using of the equipment, and to enable such use to be directed and controlled by the officials from the office, and a vast saving of time and expense thus results.

The record of the cars remaining in the yard at the end of the period for which the record book is intended to be used will be transferred to another book to be used for the next succeeding period, by filling in the columns *b*, *c*, *d*, and *e*, Figs. 1 and 3 for freight equipment, and the corresponding columns in Fig. 5 for passenger equipment, and the appropriate columns in Fig. 6 for equipment employed in yard service. Thus at the beginning of each period the record is made to contain the memoranda necessary to give the information required concerning all of the cars in the yard carried over from one period to the next.

The leaves of the book will each have

"tabs" attached thereto, on which will be inscribed the final terminal of the columns on the opposite page of the leaf. For example, the lower tab shown at the left, in Fig. 3, bears the numeral 9. This indicates that the page on the opposite side of the leaf contains the numbers the final terminal of which is 9. On the opposite side of this tab is the numeral 10. By the use of these tabs the pages bearing the terminals of the numbers which it is desired to record thereon, or to refer to, can be readily turned as desired.

Having thus fully described my said invention, what I claim as new and desire to secure by Letters Patent, is:

1. A record book for use in recording the movements of railway equipment in the yards of railway systems comprising sheets divided into a series of vertical spaces each of which spaces contains a column for the number of the car with the final terminal shown in connection with successive "third" terminals, another column for the initials of the company to which the car belongs, another column for the initials of the company from which the car was originally received, another column for the "class" of car, and several columns for recording the "received" and "forwarded" movements of each car, each sheet also containing other vertical spaces divided into columns, one of which is adapted to contain the car number, another the initials of the company owning the car, another the file number containing information concerning the car, another for special notations, said several columns of said several sheets being appropriately designated, and another sheet interposed at the end of each series of ten of the main sheets containing appropriately arranged and designated spaces for "overflow" memoranda concerning any car of any number on the 10 preceding pages, all substantially as set forth.

2. A record book for use in recording the equipment handled in railway yards consisting of sheets divided into columns appropriately designated and arranged for recording the movements of cars by numbers, each sheet containing ten successive "third" terminals, each eleventh sheet of the book being an overflow sheet containing appropriately arranged spaces for recording "overflow" memoranda concerning any car of any number in the ten preceding sheets, said overflow sheet having a section adapted to receive overflow memoranda as a continuation of any of the ten sections of each of the ten preceding pages, all substantially as set forth.

3. A railway equipment record book for use in railway yards comprising a series of sections each having a series of sheets with columns and divisions appropriately designated and arranged for containing a record of "received" and "forwarded" movements of cars, a record of the company from which the car was received originally, a record of the files containing information concerning the cars by numbers, a sheet interspersed at regular intervals at the end of each of said sections also appropriately designated and arranged for receiving "overflow" information of like character from the several spaces of each of the several sheets of the section immediately preceding, and other sheets appropriately designated and arranged for receiving other record of the equipment within the yard, whereby a complete yard record may be comprised in a single book, all substantially as set forth.

In witness whereof, I have hereunto set my hand and seal at Washington, District of Columbia, this twenty-seventh day of May, A. D. nineteen hundred and fourteen.

WALTER I. LEATHERLAND. [L. s.]
